UNITED STATES PATENT OFFICE

2,219,120

FACSIMILE SYSTEM

Frank J. Somers, San Jose, Calif., assignor, by
mesne assignments, to Farnsworth Television &
Radio Corporation, Dover, Del., a corporation of
Delaware

Application March 27, 1935, Serial No. 13,252

9 Claims. (Cl. 178—6.7)

My invention relates to a system for transmission of visual information at a distance and relates more particularly to a system designed to transmit facsimile images.

5 Among the objects of my invention are: To provide a facsimile system wherein transmission is satisfactory over a circuit or channel where the signal-to-noise ratio may be as low as 3 to 1; to provide a system adapted for the transmission 10 and reception in black and white of line drawings, handwriting, printed matter, or the like; to provide a system adapted for the transmission of printed matter and accompanying line drawings en bloc. To provide a facsimile system having minimum inertia limitations; to provide a facsimile system wherein enlargement or reduction may be made in the size of the reproduced image from that of the original field; to provide a system for the transmission of news print 15 to a distant point, utilizing the lower grades of commercial channels, either wire or radio; to provide a system of facsimile having a minimum interference factor; to provide a facsimile system capable of operating at high speed; to provide a facsimile system utilizing desirable characteristics of a grid-controlled arc rectifier; to provide a facsimile system wherein amplitude changes during transmission have a minimum effect upon the received image; to provide a facsimile-receiving system giving a simultaneous 20 recording and visual image; to provide a facsimile-receiving system wherein information can be instantly made available upon reception and be preserved in recorded form thereafter; to provide a facsimile system wherein a minimum amount of time is consumed in transmission and 25 visual reception; to provide a facsimile system utilizing the desirable characteristics of cathode ray tubes; to provide a simple and efficient means and method of transmitting facsimile images 30 over wire or radio channels; and to provide a preferred facsimile system utilizing at least in part certain desirable characteristics of any or all of the inventions disclosed and claimed in 35 the following patents and application:

60 Other objects of my invention will be apparent

or will be specifically pointed out in the description forming a part of this specification, but I do not limit myself to the embodiment of the invention herein described, as various forms may be adopted within the scope of the claims.

In comparing facsimile and telephoto transmission it will be found that facsimile is, in a number of respects, accomplished with simpler equipment. Defining the terms as herein used, telephoto transmission comprises the transmission of an original picture field and the reproduction of that field at a preferably distant receiving station in all its intermediate shades or half tones. On the other hand, facsimile transmission does not attempt to transmit half tones, but merely transmits the extreme contrasts of black and white. There is thus removed from the problem of facsimile the necessity of transmitting fine variations of amplitude due to closely adjacent shades in the original picture field. I have found that whereas suitable telephoto transmission requires adequate phase correction and a signal-to-noise ratio of at least 20 to 1, satisfactory facsimile transmission can be carried on over a radio circuit or other channel in accordance with my present invention where the signal-to-noise ratio is as low as 3 to 1. Consequently, a less expensive channel can be used for facsimile and transmission can be in the form of interrupted uniform amplitude impulses without the necessity of amplitude modulation. No substantial phase or frequency corrections are necessary, if the radio circuits and equipment are designed with ordinary care according to practices well known to the art.

For certain classes of facsimile service, as for example, the transmission of printed matter en bloc where the only detail requirement is legibility of the received image, further savings can be effected because satisfactory results can be obtained with methods of, and apparatus for, transmission, reception and synchronization much less precise and accurate than those required either in systems for telephoto transmission or television transmission.

I have found that there are certain desirable characteristics inherent in the Farnsworth system of electronic scanning, as exemplified, described and claimed in the foregoing list of patents and application, which, when combined and adapted for my new purpose will produce a preferred system which is ideal for the transmission of facsimile. It is of course to be understood that the actual apparatus used is subject to design variations according to conditions to be met for any particular installations, but in order that the broad aspects of my invention, which comprises a complete system for the transmission of facsimile be more fully understood,

I describe herein a preferred embodiment of apparatus to illustrate my invention.

In the drawings, Figure 1 is a circuit, diagrammatic and reduced to simplest terms, of a transmitter arrangement for sending over a radio channel impulses arising from scanning news print or similar subject matter.

Figure 2 is a similarly schematic diagram showing the main features of a receiving set adapted 10 to receive images from the transmitter of Figure 1 and combining the impulses received therefrom into a visual image which may be viewed by an operator and/or recorded on a sensitized film or paper.

15 As to apparatus, my invention broadly comprises a facsimile system giving a continuous process of transmission from tape or belt at the sending end, and production of corresponding automatically developed photographic tape 20 images at the receiver; together with an instantaneous visual indication of parts of the picture or newsprint at the receiver so produced that a considerable part of the picture or several lines of newsprint remains visible for a sufficient 25 length of time so that the print may be read or the quality of the received picture ascertained without the necessity of waiting for development.

Referring to Figure 1 for a description of my 30 preferred form of facsimile transmitter, the subject matter to be scanned is preferably in the form of a printed paper tape 11 which may comprise one, two or more columns of news print. The paper is progressed preferably at uniform 35 speed from a magazine not shown, by a drive wheel 12. The drive wheel 12 is preferably maintained at a uniform rate of rotation by a synchronous motor 14 which in many cases may well be an alternating current synchronous motor operating from the power mains, a similar motor 40 being preferably used at the receiver station, as will be later described. It is well known that in the United States at the present time, the majority of central power stations maintain an 45 exact frequency and many such power systems are interlocked throughout the country so that synchronous motors are, in most cases, sufficiently accurate to maintain synchronization between transmitter and receiver. If, however, 50 such controlled frequencies are not available, motor 14 may be controlled by tuning forks or similar devices as is well known in the art, and the receiver motor may be similarly controlled and synchronization maintained in any one of 55 the customary methods. As this is no part of the instant invention, no further reference will be made to this portion of the apparatus.

While it is possible to arrange the optical system at the transmitter so that images of either 60 translucent or opaque subjects can be focused on cathode 19 of dissector tube 20, the optical system for opaque subjects only is, for the sake of clarity in describing the system, shown in Figure 1. A lamp 15 is positioned in front of the tape 11 and the light therefrom is directed by means of a reflector 16 onto a picture field comprising a portion of the tape 11. Light is reflected therefrom, passed to a lens 17 and focused thereby on a photo-sensitive cathode 19 of an electronic scanning device or dissector tube 20, such as that 65 described and claimed in the Rutherford Patent No. 2,135,149, listed above, the operation of which is fully described and claimed in the Farnsworth Patent No. 1,773,980 listed above.

70 The path of the light into the dissector tube is

indicated by a line of arrows 21. The dissector tube 20 comprises an envelope surrounding the cathode 19 and is provided with a target finger 22 having therein an aperture 23 through which electrons emitted from the cathode 19 may pass 5 to impinge upon a collecting anode 24. The finger 22 is energized at a positive potential by means of an anode battery 25 and the cathode is grounded to the negative end of the battery through a battery 26. Under the impact of the 10 light in the image falling on the cathode 19 electrons are emitted from the photoelectric surface thereof in proportion to the intensity of the light striking the various portions of the cathode and are drawn thereafter towards the finger 22, 15 meanwhile being kept in parallel array by means of a focusing coil 27 energized by a focusing source 28 under the control of a rheostat 30. There is, therefore, formed in space an electrical 20 image, each elementary area of which corresponds in electron intensity to the intensity of the light falling upon elementary areas of the cathode 19. Thus, only a certain single elementary area of the electron image will enter the aperture 23 in the finger, providing the electron 25 image is left undisturbed. For the complete action of the focusing coil reference may be had to Farnsworth Patent No. 1,986,330, listed above.

If, however, the electron image is scanned past the aperture, other elementary areas of the electron image will enter the anode aperture 23 and fall upon the inner anode 24. Horizontal scanning is accomplished by the use of a magnetic scanning coil 31 which is supplied with a saw tooth current from a scanning oscillator 32 either 35 as described in the Farnsworth and Lubcke Patent No. 2,059,219, above referred to or in other ways well known in the art. Thus, as the tape 11 progresses, horizontal scanning takes place, one line following another as the tape moves 40 along its course. The distance between lines will of course be regulated by the speed of the tape 11 and the frequency of the scanning oscillator. These factors are, of course, under the control of the operator and may be regulated to suit atmospheric conditions and other requirements of 45 the service.

During scansion, electrons entering the scanning aperture 23 fall upon the collecting anode 24 to create a current which passes through the signal resistor 34 to cause a potential difference 50 which is then applied to the grid 35 of an amplifier tube 36. The output of this tube is passed through an output resistor 37, the tube being energized in the usual manner by amplifier sources 38, and thence led to the grid 40 of a "thyatron" or a grid-controlled arc rectifier having the usual grid condenser 40A and leak 40B. Such tubes are well known in the art. If supplied with an alternating anode voltage, current 55 will start when the voltage on grid 40 becomes more positive than the critical value for breakdown, and will flow from cathode 42 to anode 43 thereof for the remainder of the cycle, or for succeeding cycles as long as the grid is so energized. I prefer to bias the grid 40 by potentiometer assembly 40C.

I then energize the anode 43 of this rectifier by an oscillator 44 which may conveniently be an inductor alternator operating, for example, 60 at two thousand cycles and two hundred and fifty volts, giving an output of one hundred watts. The output of the rectifier tube is led to a keying resistor 45 and key leads 46 taken from opposite ends of this resistor and led to the input 70

47 of a radio set including an oscillator, buffer, amplifier, and radio-frequency amplifier, which radiates energy into space by means of an antenna system 49. This entire radio equipment 5 may be conventional and is shown in Figure 1 as enclosed by the dotted line 50. It should be understood that the radio set as described is not a telephone set, but is the ordinary type of radio code transmitter and it may be considered that 10 the grid-controlled rectifier, passing current from the oscillator 44, is merely keying the radio set to send out impulses of equal size and duration but in varying groups as determined by the energization of the grid of the rectifier tube which 15 in turn is controlled by the output of the di- sector tube 20. I also prefer to utilize a portion of the output of the scanning oscillator 32 after passing through a pulse amplifier 51 to energize the grid 48 of the rectifier tube 41 in order that 20 a synchronizing signal be sent over the radio transmitter at the end of each scanning line.

Thus, I provide a facsimile system wherein a radio code transmitter sends out impulses of equal size and duration, these impulses being broken 25 into groups of varying lengths in accordance with the impulses received from a cathode ray dissector tube having a cathode receiving light from the field to be transmitted, and also groups of impulses at the end of each scanning line for the 30 purpose of synchronization at the receiving end, although other methods of providing synchronization of the receiver such as by tuning forks and other methods well known to the art may be utilized if desired.

35 It should also be noted that for best results the alternator frequency should be high enough to provide one or more impulses for the smallest elementary spot of light to which dissector 20 can respond.

40 Turning to Figure 2 for a description of the receiving equipment, impulses radiated by the transmitter of Figure 1 are received on a receiving antenna 52 and led to a radio receiver 54 of the usual type, the output from this receiver being 45 led to the control grid of a receiving grid-controlled rectifier tube 55. The bias of this grid can be adjusted by the usual potentiometer battery assembly 56. The anode 57 of this grid-controlled rectifier is energized by a receiving oscillator 58 which may be, for example, an inductor alternator operating at 5,000 cycles. It is not necessary of course that the output of this receiving rectifier be as large as similar tubes used in the transmitter as here the power necessary to 50 operate subsequent apparatus is not nearly so great as the power required to key the radio transmitter. A vacuum tube oscillator can also be used.

55 The potential drop across an output resistor 60 in the anode circuit of the rectifier tube 55 is led through an output lead 61 first to energize the grid 62 of a visual cathode ray tube 64 and also to the grid 65 of a recording cathode ray tube 66 through blocking condenser 67 and 68, respectively. The grids of both cathode ray tubes are biased by the usual potentiometer battery assemblies 70-70 attached to the grid at one end through grid resistors 71-71 and at the other end to filament power transformers 72-72 connected 75 to the filaments 74-74 of the respective cathode ray tubes. Both anodes 75-75 of the respective tubes are energized from the common anode supply 76 and each of the tubes is provided with a focusing coil assembly 77, in order to provide a sharp spot for the cathode ray beam on both the

visual cathode ray tube screen 79 and the recording cathode ray tube screen 80. A portion of the output energy from the receiving rectifier tube 55 is passed through a blocking condenser 81 to a pulse amplifier tube 82 and is used to control the oscillation period of a receiving scanning oscillator 84 through grid transformer 85 which also carries the windings 86 for the output of the scanning oscillator. The output is transmitted through pulse leads 87 and divided between a 10 horizontal visual tube scanning coil 89 and a horizontal recording tube scanning coil 90. Thus, the scanning pulses, which are transmitted at the end of each scanning line, are utilized to control the oscillation of the receiving scanning oscillator so that horizontal synchronization will be exact. Automatic synchronization is thus obtained.

Positioned to receive light from the recording tube screen 80 is a lens train 91 forming a portion 20 of a camera case 92 enclosing a reel 93 of film or sensitized paper 93' which is passed over a drive roll 94 to intercept the light beam focused thereon by the lens 91. The drive roll 94 is rotated by a synchronous motor 95 which, as explained 25 above, may be attached to the alternating current mains so as to maintain synchronism with the transmitter or may be tuning-fork controlled as is well known in the art. The film or paper passes from the camera into a developing case 96 30 through developing chambers 97 and 98 thence to a dryer not shown and finally emerges in the form of an exposed developed and dried record 109. I do not wish in any way, however, to be limited to this particular form of recording device as 35 there are many others which will suggest themselves to those skilled in the art in order that a fixed and permanent image on a record from a source of light be created, and the particular means shown is not essential to my invention. 40

I also provide for the visual cathode ray tube 64 a vertical scanning coil 101 supplied with impulses from a visual tube scanning oscillator 102. I prefer to utilize a certain definite type of material for the visual tube fluorescent screen 79, 45 preferably a screen formed from a material having a time lag. It is well known in the art that printed matter can be reproduced with a minimum of five scanning lines and I prefer to have the time lag of the monitor tube at least sufficiently long so that five scanning lines will appear on the screen at the same time so that completely formed printed matter will be visible. In case a large number of head lines or similar higher letters are to be transmitted, I prefer to have the 50 time lag of considerable length; in fact, I have found that thirty seconds is a proper timing which will encompass most of the situations arising in newspaper copy. I, therefore, adjust the frequency of the visual tube vertical scanning 55 oscillator 102 to have a frequency which is considerably shorter than the lag of the fluorescent screen, so that material appearing at the top of the fluorescent screen will just fade out in time for the next traversal of the screen. Providing a 60 thirty-second time lag is used, several lines of printing will be visible at any one time and then will gradually fade out to make way for the next few lines. With this arrangement it is possible to obtain by visual inspection of the visual tube 70 fluorescent screen 79 the transmitted information instantaneously if desired, with the assurance that a permanent record is meanwhile being made by the action of the recording camera photographing images appearing on the recording tube 75

screen 80 on the film 93'. This permanent record, of course, will not be available except after the short interval necessary for the film or paper to make the trip through the developing and fixing tank. It will also be obvious that the visual tube can be used as a monitor for the adjustment of the circuits for proper reception, and it is also within the scope of my invention that such adjustments as made to the visual monitor will be linked with adjustments of the recording tube so that it will not be necessary to inspect the actual image on the recording tube screen.

As mentioned above, the character of the radio signal transmitted between stations is merely that of a series of dots which are initiated as impulses having a uniform amplitude. Also, by the use of a grid-controlled keying relay as described, any ordinary continuous wave transmitter suitable for code messages can be used for transmission, the only requirement being that the power supply source have ordinarily good regulation. In fact, neither the transmitter per se nor the actual radio receiver need be other than ordinary commercial apparatus designed for code work.

If, during transmission, there should be variation in the amplitude of the signals due to intermediate conditions so that the signal-to-noise ratio varies, I have found that if a signal-to-noise ratio of 3 to 1 is obtained at the receiving end, satisfactory reproduction of the transmitted images will be obtained. This is due to the fact that the rectifier is capable of differentiating within a much smaller margin than 3 to 1 and I have merely selected this low value as illustrative, as the actual value will be dependent somewhat on the design of the rectifier tube. In any event, the signal-to-noise ratio which can be effectively handled by the receiver need be only a safe operating value above threshold sensitivity of the keying relay. The grid bias is adjusted so that the tube will not break down under noise impulses, but will do so under signal impulses.

The speed of transmission of material in number of words per minute which can be obtained with the apparatus as above described is ample for facsimile purposes. A speed of 20,000 words per hour—333 words per minute—can be obtained commercially in continuous operation with the optical, photographic and mechanical devices herein described. This speed is sufficient for transmitting the facsimile of an eight page newspaper—40,000 words—in two hours and is about eight times as fast as the telegraph printers now widely used for news service. The above figures are based upon the use of existing commercial transmitters, channels and receivers and if special equipment is substituted for these factors, a considerably greater speed can easily be obtained.

The preferred embodiment of the apparatus, as shown and described, is designed to operate on a basis of 100 picture elements per printed character, allowing a 100 element square to include each character and the space between the lines below each character. For types and spacings of printed lines as ordinarily used in present work, there will be from 5 to 7 of a possible 10 scanning lines available for forming each letter. This amount of detail will be more than sufficient for 100 per cent legibility at the receiving end.

Under these conditions, the frequency required for a transmission speed of 333 words per minute allowing an average of 5 letters and one space

for each word will be 1665 cycles per second. This of course, is the maximum frequency as the average frequency transmitted will be less because of the large percentage of dead space in the printing. The maximum frequency encountered will therefore be easily handled by the dissector and receiver tubes as they have no lag at all at any reasonable frequency and will also be easily handled by the grid-controlled rectifier tube as the frequency it is called upon to handle is much too low to be affected in any way by the deionization time of the device.

In considering the type of material to be transmitted by my preferred embodiment here shown, I have found that the maximum number of printed letters per line per unit height of letters is limited only by the optical resolving power of the transmitting and receiving tubes. The maximum ratio of length of printed line to height of individual letters will be about 60 to 1 in the apparatus described. This means, therefore, that in transmitting news print a maximum width of two columns can be transmitted at any one time. Since the process of transmission is continuous, however, there is nothing against such a procedure as it merely means that a newspaper page at the receiver will arrive in the form of four strips, one following the other. These strips can later be assembled in the form of the original paper. By refocusing the lens at the transmitter other material such as typewriting may be transmitted, no other adjustments being necessary. Line drawings of almost any size can be transmitted either as a whole or in portions later to be assembled, the size again depending upon the resolving power required for the proper detail in the received image.

It should be noted that, while the resolving power of both transmitter and receiver tubes are limited by their effective apertures and therefore control the minimum size of received elements, the optical systems associated with the transmitter and receiver are both adjustable and separately so. This means that no initial preparation of material to be transmitted need be made. In explanation of this feature of my invention, I would like to point out that in the usual type of facsimile transmitter, the actual field scanned by the transmitter is almost invariably made especially for the purpose in respect to its dimensions. In other words, drum type telephoto and facsimile apparatus such as is well known in the art require that the material to be transmitted be reduced or enlarged and transferred as a special print of standard dimensions which can be mounted upon the transmitting drum. The received facsimile is limited to the dimensions of a drum and it is almost the invariable custom to have the transmitting and receiving drums of the same exact size. The print which is to be transmitted and the print which is received are, therefore, both identical in size and it is quite often the case that the time factor involved in preparing the material to be transmitted in the form of a special print either reduced or enlarged is often important in transmitting spot news.

My invention, however, obviates any special necessity for any particular size of the transmitted material providing always that it is not too small to be handled by the equipment. Therefore, the tape 11 can be an imageless tape upon which heterogeneous material to be transmitted is attached and if the material to be transmitted is larger than or smaller than, within

the limits of the apparatus, the image desired on the receiving end, the optical system comprising the image tape 11, lens 17 and cathode 19 in the transmitter may be adjusted so that the image 5 thrown upon the cathode 19 of the transmitter may be of the proper size irrespective of the size of the material itself, as long as the material is of high contrast and plenty of light is always available. A similar adjustment can be made 10 between the screen 80 of the receiving tube 66, the lens 91 and the film or paper 93, thus providing a material advantage in my system, which is not present in the devices of the prior art.

It should be noted that, while the transmitted 15 signals are interrupted sequences, they are rectified at the receiver and supplied as maximum and minimum voltage values to the receiving rectifier. The output of this rectifier again is interrupted, and preferably at a higher frequency 20 than the interruption taking place at the transmitter. The receiving interruptions, however, are not visible in the monitor tube, due to its screen lag, nor on the recorded image, as the photosensitive surface is cumulative in response, 25 and the frequency can be made sufficiently high to cause overlap.

It is of course obvious that my invention is not to be limited to the use of a radio-frequency carrier in space or over wire lines, and that the transmission 30 may be accomplished without departing from the spirit of my invention over wire lines or similar channels utilizing direct-current transmission currents modulated in accordance with the output of the grid-controlled arc 35 rectifier 41.

I claim:

1. In combination, a transmitter, a grid-controlled arc rectifier connected to key said transmitter, said rectifier being energized by an alternating source, an electron image dissector, a picture field within said dissector, means within said dissector for creating an electron image of said picture field, means for moving said picture field uniformly along one dimension, means to move 40 said electron image in another direction to produce line-by-line scansion thereby creating a train of picture impulses, and means for applying said impulses to the grid of said rectifier to control the output thereof.

50 2. The combination as in claim 1 wherein the picture field is moved vertically and is scanned horizontally.

3. The combination as set forth in claim 1,

the transmitter being a radio transmitter of high-frequency waves.

4. The combination as set forth in claim 1, with means for moving a succession of picture fields into position for scansion.

5. A facsimile receiving system comprising a receiver adapted to receive transmitted facsimile impulses, a cathode ray tube containing a screen having a relatively long time lag, a cathode ray tube containing a screen having a relatively 10 short time lag, means for simultaneously modulating the beam of both tubes in accordance with said impulses, means for moving the beam of the first tube in two dimensions to produce a visual picture thereon, means for moving the beam of 15 the second tube in one dimension only, and means for applying the light from the screen of the second tube to a light-sensitive surface moving in a direction to produce a residual picture thereon.

6. The combination as set forth in claim 5 with means for moving said light-sensitive surface in synchronism with the picture field originating said impulses.

7. The combination as set forth in claim 5 25 with means for limiting received impulses to a constant amplitude.

8. A facsimile system comprising means at a sending station for scanning printed matter line for line with at least five scanning lines per line 30 of printed matter, a receiving station, and a cathode ray type of image reconstructing device at said receiving station having an image viewing screen with a time lag enabling at least five scanning lines to be viewed simultaneously. 35

9. In combination, a transmitter, a grid-controlled arc rectifier connected to key said transmitter, said rectifier being energized by an alternating source, a picture field, means for scanning said field to produce a train of picture impulses and means for applying said impulses to the grid of said rectifier to control the output thereof, said scanning means comprising an electron image dissector, an optical system adapted to project an image of said picture field into said 40 electron image dissector for producing an electron image within said electron image dissector, means for uniformly moving said picture field in one direction, and means for moving said electron image in a direction transverse to said first-named direction. 45

FRANK J. SOMERS.
